[57] CLAIM

The ornamental design for a cart for snowmobiles or the like, as shown and described.

DESCRIPTION

FIG. 1 is a front and top perspective view of a cart for snowmobiles or the like showing my new design;.

FIG. 2 is a top plan view thereof;

FIG. 3 is a bottom plan view thereof;

FIG. 4 is a side elevational view thereof, the opposite side view being a mirror image of that shown;

FIG. 5 is a rear elevation view thereof; and

FIG. 6 is a front elevation view thereof.
